UNITED STATES PATENT OFFICE.

ERVIN V. SWEET, OF ATTLEBORO, MASSACHUSETTS, ASSIGNOR TO C. O. SWEET AND SON COMPANY, A CORPORATION OF MASSACHUSETTS.

DESIGN FOR A BRACELET.

45,163.

Specification for Design.

Patented Jan. 13, 1914.

Application filed November 12, 1913. Serial No. 800,685. Term of patent 7 years.

To all whom it may concern:

Be it known that I, ERVIN V. SWEET, a citizen of the United States, residing at Attleboro, in the county of Bristol and State of Massachusetts, have invented a certain new, original, and ornamental Design for a Bracelet, of which the following is a specification.

In the accompanying drawing which forms a part of this specification, the figure is a perspective view of a bracelet embodying my new design.

I claim:

The ornamental design for a bracelet, as shown.

ERVIN V. SWEET.
